United States Patent Office.

FLORENT J. VANDERVINNE, OF BRUSSELS, BELGIUM.

Letters Patent No. 66,425, dated July 2, 1867.

IMPROVED EXCAVATOR OR DIGGING MACHINE.

The Schedule referred to in these Letters Patent and making part of the same.

TO ALL TO WHOM THESE PRESENTS SHALL COME:

Be it known that I, FLORENT JOSEPH VANDERVINNE, of Brussels, in the Kingdom of Belgium, have invented an improved Excavating or Digging Machine; and that the following is a full, clear, and exact description of the principle or character which distinguishes it from all other things before known, and of the usual manner of making, modifying, and using the same.

This machine, which is intended to make trenches or cuttings in the forming of railways, canals, and generally for the excavation of all kinds of open earthwork, and even for clearing uncultivated land to a great depth, is fixed on an iron frame or carriage, carried by three pairs of cylindrical wheels, or by three pairs of double wheels. All the mechanism is fixed on this frame, which is propelled at a speed of about one hundred and forty-one feet an hour.

The frame or carriage: I will take, for example, a rectangular frame, about twenty-four feet long by six feet six inches wide. The axles support a second frame about twelve feet above this latter, by means of standards, connected by tie-pieces, and strongly fixed by iron angle-pieces. The front supports are inclined backwards, in consequence of the arrangement of the mattocks or picks.

The mattock or pick shafts and their action: In front of the frame are two wrought-iron vertical shafts, about ten feet high and about three feet six inches apart, turning on their axes from the exterior towards the interior. Two chairs bolted on the frame support these shafts, their upper extremities passing through and turning in the parts of the iron framework, forming the long sides of the upper frame, projecting past the inclined standards. Each shaft carries twenty-one forged-iron double mattocks or picks with steel points, keyed on so as to form a screw, and in such a manner, that during the action of the mattocks, those on one of the shafts pass in the corresponding spaces left between the mattocks of the other shaft. Motion is given by bevel-gearing wheels placed above the frame, which wheels are drawn by a series of pulleys communicating with the motive shaft, the whole being proportioned so as to give to the mattock-shafts a speed of about twelve turns per minute. The length of the mattocks diminishes progressively from the top to the bottom, so that the surface first cut may be a trapeze about ten feet wide at its upper extremity, seven feet six inches at its lower extremity and about nine feet three inches high. The object of this arrangement is to form a slope to the trench or cutting, for fear of a slip. The mattocks cut and detach the earth and throw it behind. A curved plate is placed at each side, so that the earth shall not be thrown sideways. It is then received in troughs fixed on an endless chain, articulated and moved by two hexagonal pulleys. These troughs turn it over on an endless chain, whence it is thrown into the carts for carrying it away, and which are situated, according to the requirements and arrangements of the places, behind or at the side of the carriage.

For the transportation of the machine, and not to injure the iron wheels, two axles are adapted to receive wheels of a larger diameter. The frame moves forward by means of a horizontal shaft, carrying three endless screws, placed so as to drive three gearing-wheels wedged on the axles. These endless screws make about six revolutions per minute, and as the gearing-wheels have twenty teeth, they make about one and a half turns in five minutes, (thirty teeth.) The mattock-shafts make, as above described, twelve turns in the same time, and as each mattock has two points, it is evident that the earth is struck forty times per minute at the same height. If the mattocks encounter stones no accident will result from it. Pieces of stones are at first detached by the steel ends of the picks, and in a few seconds, in consequence of the repeated shocks, the stones will be detached and roll in the troughs, following the direction of the screw. The arrangement of the picks around the shafts offers this advantage, *videlicet*, that a constant number of the picks cuts the earth at one time without intermittence, and that the machine insinuates itself insensibly in the cutting without apparent effort and without sudden shock, thus rendering it very advantageous for the application of steam power in any kind of earth-work. The motive steam engine is situated at the back of the frame, together with its boiler and its reservoir for the water necessary for its daily work. It should be of ten to twelve horse-power, and turns a main shaft placed perpendicularly to the direction of the line of work. The whole arrangement is a combination of mechanical parts, so connected as to work the mattock-shafts forming the screw. The machine moves forward by means of the double wheels on which it rests. These wheels are divided into four parts, two solid and two hollow, for movable rails, each advancing by means of the mechanism. The six wheels always run on two rails, and the

two others advance about one foot eight inches in front. These movable rails serve to support the carriage without sinking, as the carriage draws its rails by its mechanism.

Description of the Drawings.

Figure 1, Sheet 1, is a plan; and Figure 2, Sheet 2, a side elevation of my improved excavating or digging machine.

No. 1, frame or carriage; No. 2, locomobile; No. 3, supports of the mattock-shafts J; No. 4, iron angle-pieces, bolted to the uprights of the frame.

A, pulleys placed on the shaft of the locomobile; B, shaft on which is placed the drum K, which moves the trough chain; C, pulley placed on the shaft B, and driving the trough chain; D, pulley placed on the shaft D, and driven by the pulley F; G H, bevel-gearing, driving the vertical shafts J, on which the picks L are placed; M, trough chain; N O, pulley driving the shaft P on which the screw Q is placed; R, gearing driving the shaft S, on which are fixed the endless screws U, acting on the gearing V, fixed on the axles of the wheels T of the carriage; X, axles of the wheels T; Z, shaft of the pulley F.

What I claim, is—

1. The general arrangement and construction of an excavating or digging machine, as hereinbefore described and represented in the accompanying drawings.
2. The peculiar arrangement and construction of the picks, in combination with the endless chain, carrying the troughs and mechanism for working the same, as hereinbefore described and represented in the accompanying drawings.

In testimony whereof I have hereto set my hand and affixed my seal this 31st day of December, one thousand eight hundred and sixty-six.

FL. J. VANDERVINNE.
